UNITED STATES PATENT OFFICE.

FRANCIS MEISEL, OF BOSTON, MASSACHUSETTS, ASSIGNOR TO THE CARTER-CRUME COMPANY, OF NIAGARA FALLS, NEW YORK.

NUMBERING ATTACHMENT FOR PRINTING-MACHINES.

SPECIFICATION forming part of Letters Patent No. 542,369, dated July 9, 1895.

Application filed April 25, 1894. Serial No. 509,004. (No model.)

To all whom it may concern:

Be it known that I, FRANCIS MEISEL, a citizen of the United States, residing at Boston, in the county of Suffolk and State of Massachusetts, have invented certain Improvements in Numbering Attachments for Rotary or Cylinder Printing-Machines, of which the following is a full, clear, and exact description, reference being had to the accompanying drawings, making part of this specification, in which—

Figure 1 is a side elevation of a cylinder printing-machine having my improved numbering attachment applied thereto. Fig. 2 is an end elevation of the same, looking from the left-hand side of Fig. 1 toward the right. Fig. 3 is a longitudinal vertical section on the line 3 3 of Fig. 2, looking in the direction of the arrow 10. Fig. 4 is a similar section on the line 4 4 of Fig. 2, looking in the direction of the arrow 12. Fig. 5 is an enlarged detail of the ratchet-and-pawl mechanism which actuates the numbering-wheels. Fig. 6 is an enlarged detail of the inking apparatus for inking the numbering-wheels.

My invention has for its object to improve the construction of numbering attachments for rotary or cylinder printing-machines; and my invention consists in the construction and combinations hereinafter described and claimed.

In the said drawings, A represents the framework of a cylinder printing-machine.

B is the type or plate cylinder to which the forms or plates are secured in the usual manner, and C is the impression-cylinder.

D represents the mechanism for inking the type-forms on the cylinder B, which mechanism is of the usual construction and will therefore require no further description.

The cylinders B C are mounted on shafts b c, which are connected so as to rotate together with the same surface velocity by gears d e, the shaft b having secured to it, outside the frame-work, the driving-pulley E.

To a horizontal shaft G, parallel with the shafts b c, and having its bearings in the framework, are rigidly secured the numbering or type wheels H H, having around their peripheries a series of projections f, as shown

in Fig. 5, the faces of which are provided with consecutive numbers up to any desired limit—for instance, fifty or one hundred—to correspond with the numbers desired to be printed on the series of sales-slips or other articles passing through the machine. The number of printing-wheels H on the shaft G will correspond to the number of separate series of sales-slips or other articles extending across the width of the web or sheet of paper I, there being one or more printing-wheels for each series.

The web of paper I to be printed is taken from a roll K, mounted on a horizontal shaft 15, supported in suitable bearings in uprights 16, the paper thence passing under a guide-roll 18, over a guide-roll 20, thence up between the numbering-wheels H and the impression-cylinder C, and between the latter and the type-cylinder B to the take-up roll L, upon which it is wound after being numbered and printed.

I will now describe the manner in which the printing-wheels H are rotated intermittently to bring the numbers on their peripheries consecutively into contact with the web or sheet of paper I as it passes up between said wheels H and the impression-cylinder C before receiving the impressions from the forms on the type-cylinder B.

To the shaft G, outside the framework, is secured a ratchet-wheel M, which is actuated by a pawl g pivoted to the outer end of an arm h, which is pivoted loosely upon the shaft G, the pawl being kept in contact with the teeth 75 of the wheel M by a spring i. To the arm h is pivoted an arm k, which is bifurcated at its lower end and embraces a shaft m, to which is secured a cam N, which acts upon a roller n mounted upon a stud projecting from the 80 arm k, a spring p being secured to the lower end of the arm k and to a pin projecting from the framework, whereby as the cam N is rotated the ratchet-wheel, and with it the shaft G and numbering-wheels H, are rotated a distance equal to that between two consecutive numbers on said wheels at each complete revolution of said cam, the numbering-wheels being left at the completion of each movement with the projections f out of contact 95 100.

with the impression-cylinder, as shown in Fig. 5, the latter being thus free to continuously revolve independently of the numbering-wheels and, in connection with the type-cylinder B, draw the paper up through the space thus left between the wheels H and cylinder C until it is desired to print the next number, when the wheels H are again moved by the ratchet-and-pawl mechanism just described

- 10 to bring the next consecutive numbers into contact with the paper and press the same against the surface of the cylinder C to produce the impressions as required. The cam-shaft *m* is provided with a pinion *q*, Fig. 4, which is connected by a train of intermediate gears *r s* with a gear *w* on the shaft *c*, whereby as the latter is rotated motion is communicated to the cam-shaft *m*, and thence to the cam and the ratchet-and-pawl mechanism
- 15 20 above described.

By changing the size of the pinion *q* on the cam-shaft *m* the number of revolutions of the latter may be made to correspond to the number of forms extending in a single line or series around the circumference of the type-cylinder B, thus rendering the machine adjustable to suit the requirements of the case, a number being printed at each complete revolution of the cam N.

- 25 30 The above-described mechanism for intermittently rotating the numbering-wheels H is so constructed and timed that it will positively move said numbering-wheels with the same surface velocity as that of the impression-cylinder C during the time that the types on said wheels H are in contact with the paper, thereby effectually preventing any blurring or rubbing of the impressions and insuring the production of perfect work.

- 35 40 To prevent the numbering-wheels from being carried by their own momentum farther than is due to the motion of the actuating-pawl *g*, I employ a friction device consisting of a brake P, which is kept constantly set up in contact with the periphery of a bearer-wheel Q, secured to the shaft G of the numbering-wheels. This brake P is mounted upon an eccentric stud *y*, projecting from a horizontal arm R, extending out from the framework, said stud having a square end 21, as shown in Fig. 4, by which it may be turned to keep the brake firmly up to the wheel Q with the desired amount of pressure as the surfaces in contact become worn away. *a'* is 45 a set-screw by which the stud *y* is clamped in position after the brake has been set up with the required amount of pressure.

I will now describe the inking apparatus or mechanism by means of which the numbering-wheels H are supplied with ink.

- 50 55 The two numbering-wheels H are both inked by a single form-roller S, the shaft of which is supported at its opposite ends in boxes 25, fitted to slide in slots 26 at the lower ends of 60 two arms T T, loosely mounted on the numbering-wheel shaft G and connected together

by a tie-rod V, the whole forming a vibrating supporting-frame for the form-roller, to the shaft of which is secured, at its opposite ends, two small friction-wheels b' b', which are 70 adapted, when the form-roller is in contact with the numbering-wheels, to bear one against the periphery of the bearer-wheel Q and the other against the periphery of a similar bearer-wheel W, also secured to the numbering-wheel shaft G, whereby as the numbering-wheels H are moved the form-roller will be rotated in contact therewith and with the same surface velocity to ink the same, as required.

X is the metal ink-distributing cylinder by which the form-roller is supplied with ink and by which the latter is rotated by frictional contact when not in contact with the numbering-wheels. This cylinder X is 85 mounted on a shaft c', having its bearings in the framework and carrying at one end a grooved pulley d', Fig. 2, which is driven by a cross-belt e' from a grooved pulley f' on the shaft c of the impression-cylinder C, the cylinder X taking ink from the roller 35, with which it is always in contact, and being also vibrated in the usual manner by means of a cam-wheel g', Fig. 2, on its shaft co-operating with a roller h', mounted on a stationary stud 95 projecting from the framework.

It will be obvious that if the form-roller S derived its motion wholly or at all times from the cylinder X it would, on account of the speed of the latter, have a surface velocity 100 greatly exceeding that of the numbering-wheels H, and hence the types thereon would tear and injure the form-roller, and the latter would also only imperfectly ink the types. It is therefore desirable to give the form-roller 105 the same surface velocity as the numbering-wheels when inking the same. This I accomplish by moving the form-roller away from the cylinder X and simultaneously bringing it into contact with the numbering-wheels, 110 and at the same time bringing the friction-wheels b' into contact with the bearer-wheels Q W, which are of the proper diameter, and arranged to revolve the form-roller with the same surface velocity as the numbering-wheels while in contact therewith.

The arms T are rocked to move the form-roller toward and away from the cylinder X by a lever A', connected with one of the arms T by a link 30, Fig. 6, said lever A' being fulcrumed on a stud projecting from the framework, and carrying at its upper end a cam-roller 32, which is acted upon by a cam B' on the shaft c of the impression-cylinder C, which cam moves the lever A' against the resistance 125 of a spring i', which encircles a rod k', pivoted to the lever A' and sliding through a stationary guide m', the spring bearing at one end against said guide m' and at the opposite end against a fixed collar 40 on the 130 rod k'.

Over each of the boxes 25 of the form-roller

shaft is a cam or incline q' , (shown in Fig. 6,) formed at the end of a stationary arm r' , secured to the framework, each box 25 being kept in contact with its cam q' by a spiral 5 spring s' , placed beneath it in a recess 26, and, consequently, as the arms T are rocked outward by the action of the spring i' and cam B' to disconnect the form-roller S from the inking-cylinder X, the boxes 25 will follow the inclined surfaces of the cams q' , thus allowing the springs s' to force the form-roller S upward into contact with the numbering-wheels H to ink the same, the friction-wheels b' being at the same time brought into contact with the bearer-wheels Q W, which then instantly cause the form-roller to rotate with the same surface speed as the numbering-wheels, the arms T, as they continue to move outward, causing the form-roller to ink one or more of the types on each numbering-wheel whether said wheel is in motion or at rest. The arms T are then swung downward by the cam B' to bring the form-roller again into contact with the ink-cylinder X, which causes 5 the boxes 25 to follow the inclined cams q' against the resistance of the springs s' , thus withdrawing the form-roller S out of contact with the numbering-wheels H, as required, leaving it free to be rotated at a much faster rate of speed by frictional contact with the inky-cylinder X. The cam B', here shown, is constructed to operate the form-roller arms T three times during a single revolution of the impression-cylinder C, but it may be made to 5 operate said arms only once or as many times as may be desired during said revolution of the impression-cylinder C.

$t' t'$ are rods provided at their upper ends with heads 36 and encircled by the springs s' , which take a bearing on said heads and against the lower ends of the recesses 26 in the arms T. These rods are provided at their lower ends with finger-eyes u' , by which said springs may be pulled down and held when it is desired to remove the form-roller from its supporting-frame or replace it therein.

What I claim as my invention, and desire to secure by Letters Patent, is—

1. The combination with a numbering or printing wheel, of a form-roller mounted to rotate freely in a movable bearing in a vibrating frame, mechanism for swinging said frame, wheels for driving the form-roller from the axis of said numbering wheel and at the same surface velocity therewith, means for actuating the form roller bearings to throw the form-roller into and out of operative connection with the numbering wheel when the frame is vibrated, and a driven ink supplying cylinder, with which said form-roller contacts and by which it is rotated when out of contact with the numbering wheel, substantially as set forth.

2. In a cylinder-printing-machine, the combination, with the impression-cylinder having a continuous rotary motion, of an intermit-

tingly rotated numbering-wheel parallel and co-operating therewith and having the same surface velocity as the impression-cylinder during the time that it is printing the numbers on the paper in contact with said cylinder, a ratchet-and-pawl-mechanism for intermittently rotating the numbering-wheel, and a rotary cam for actuating the ratchet-and-pawl-mechanism, substantially as set forth. 70 75

3. In a cylinder-printing-machine, the combination, with the impression-cylinder having a continuous rotary motion, of an intermittently rotated numbering-wheel mounted on a shaft provided with fixed bearings; said wheel having projections provided on their faces with numbering-types, said numbering-wheel having the same surface velocity as the impression cylinder during the time that it is printing the numbers on the paper, a 80 85 ratchet-and-pawl-mechanism for intermittently rotating the numbering-wheel, and a cam and spring for actuating the ratchet-and-pawl-mechanism, said cam being mounted on a shaft connected by gears with the shaft of 90 the impression-cylinder, substantially as described.

4. In a cylinder printing-machine, the combination with the impression cylinder having a continuous rotary motion and an intermittently rotated numbering wheel co-operating therewith and having the same surface velocity as said cylinder during the time it is printing the numbers on the paper, of a form-roller supported in a vibrating frame, means for alternately throwing the form-roller into and out of contact with the numbering wheel and driving it from said numbering wheel and at the same surface velocity therewith, and a driven ink-supplying cylinder into contact 105 with which said form roller is thrown and by which it is rotated when not in contact with said numbering wheel, substantially as set forth. 100

5. In a cylinder-printing-machine, the combination, with the impression-cylinder and an intermittently rotated numbering-wheel co-operating therewith, of the form-roller S mounted in a vibrating frame and having its shaft provided with friction wheels b' , the 110 115 bearer-wheels Q, W, on the shaft of the numbering-wheel adapted to rotate the form-roller with the same surface velocity as the numbering-wheel by frictional contact with said wheels b' , means for vibrating the form-roller supporting-frame, and the cams q' and springs s' , whereby the form-roller is alternately brought into contact with the numbering-wheel and the ink-supplying-cylinder X as the form-roller-frame is vibrated, substantially as 120 125 set forth.

6. In a cylinder-printing-machine, the combination of the impression-cylinder, an intermittently rotated numbering-wheel, a form-roller mounted in a vibrating supporting-frame and adapted to be brought into contact with the numbering-wheel, means for rotating 130

the form-roller with the same surface velocity as the numbering-wheel, the ink-supplying cylinder X adapted to rotate the form-roller at an increased speed by frictional contact therewith when said form-roller is not in contact with the numbering-wheel, the cams q' , springs s' and the mechanism for vibrating the form-roller-frame consisting of the cam

B', lever A', link 30, and spring i' , all constructed to operate substantially as set forth. 10
Witness my hand this 20th day of April,
A. D. 1894.

FRANCIS MEISEL.

In presence of—

P. E. TESCHEMACHER,
S. V. MERXSCHINSKY.
